INVENTOR

UNITED STATES PATENT OFFICE.

EMORY STOCKWELL, OF STAMFORD, CONNECTICUT, ASSIGNOR TO THE YALE
LOCK MANUFACTURING COMPANY, OF SAME PLACE.

DIAL FOR PERMUTATION-LOCKS.

SPECIFICATION forming part of Letters Patent No. 240,783, dated April 26, 1881.

Application filed March 16, 1881. (Model.)

To all whom it may concern:

Be it known that I, EMORY STOCKWELL, of Stamford, in the county of Fairfield and State of Connecticut, have invented certain new and useful Improvements in Dials for Combination Locks, of which the following is a specification, reference being had to the accompanying drawings, in which—

Figure 1 is a front elevation, partly in section, of an ordinary combination-lock dial and ring with my improvements applied. Fig. 2 is a detailed view of a detached section. Fig. 3 is a perpendicular central section through the line 3'3' of Fig. 2. Fig. 4 is a view showing the parts in section on line 4'4' of Fig. 2, and Fig. 5 shows a section of a key.

Combination or dial locks, as commonly constructed, for safes, vaults, &c., have this defect, that when standing unlocked, as they usually do during the day-time when safe-doors are open, any one expert with respect to such locks can easily pick up the combination of their tumblers by manipulating the dial. This fact is a constant source of danger to users of such locks, since it enables any one who may obtain access to them during the day to feel out the combination, and thus possess himself of its secret for illegitimate use. To guard against this danger various devices have been resorted to, one of which is the entire covering over of the dial by a box or lid attached to the door of the safe or vault.

The main object of my improvement is to protect the lock from this danger, and accordingly I provide a small supplemental lock within the dial-ring to secure the dial from turning, and thus I effectually prevent surreptitious discovery of the secret of the combination upon which the lock is set; but the utility of my invention extends still farther. It is well known that it is somewhat inconvenient and consumes some time to lock and unlock a safe-door with a good combination-lock which affords a high degree of security. Consequently it is usual, as remarked above, for bankers to leave their safe-doors open during the business hours of the day, or else sometimes to apply separate key-locks to them to temporarily secure them, and to avoid placing too strong temptation before clerks and employés.

An important advantage incident to my improvement is that it answers the purpose of a separate key-lock for a safe-door that is also provided with a secure combination-lock, so that in the ordinary course of business during the day when a banker has occasion to close and fasten his safe-door at frequent intervals he is enabled to do so without working his combination-lock and without the ordinary extra key-lock. By employing my supplemental dial-lock he is enabled to throw the bolts of the safe-door and check them with the bolt of the combination-lock without rotating the dial far enough to disturb the combination, and then to secure his door by locking the dial with my supplemental dial-lock, so that the dial cannot be rotated to retract the combination-lock bolt, and thus the door-bolts are efficiently checked. The proprietor or proper officer by using his dial-lock key can instantly release the temporary fastening, and is thus able to quickly open the safe, and as quickly close and secure it again.

Proceeding now to a description in detail of my invention by reference to the letters upon the accompanying drawings, A indicates a dial-ring of ordinary form; and B a graduated combination-dial rotating within the ring, as shown, by means of a knob, C, for operating a combination-lock spindle. I pivot two or more tumblers, D, upon a hollow post, E, of the dial-ring, and provide them with a spring, F, which tends to keep their notches G out of alignment with the gate H, carried by the curved spring I, which is secured, as shown, along the inner face of the dial-ring. To the back of the dial-ring I secure a small segmental plate, K, from which projects the key-post L. In the face of the dial-ring I cut a key-hole, M, suitable to receive a key, N, adapted to oscillate the tumblers, so that their notches will be in alignment with the gate H, and also adapted to press the gate H into the tumbler-notches. I form a small recess, O, in the rim of the dial, suitable to admit the outside edge of the gate H. From this construction it will be perceived that the gate H, tends by force of the spring I to bear outward, so as to enter the recess O, in the rim of the dial, and thus lock the dial and prevent it from turning. The insertion

and operation of the key will force the gate H into the tumbler-notches and unlock the dial, when it may be turned at pleasure while the key remains in the lock. When the key is turned back and removed, however, the lock will, so far as the action of this mechanism is concerned, always be locked, provided the recess O is opposite the gate, or when it comes opposite the gate by turning it; but as it is not always desirable to have the dial locked in place, or liable to become locked in place upon the removal of the key, I provide a pivoted stop, P, which projects through a slot, Q, in the dial-ring to the outside of the ring, as shown in Fig. 1. This stop, when turned in the direction of the arrow, bears against the spring I and prevents its throwing the gate out of the tumbler-notches and locking the dial, and when turned in the opposite direction, it is simply placed out of action, and permits the spring to cast the gate into the locked position. By means of this stop P the lock can be set so as to be inoperative when desired, and also so that by tripping the stop with the

finger the lock will be brought into operation. The result is that the user can unlock the dial and set the stop P and withdraw his key, and then rotate the dial as many times as necessary, and then trip the stop P with his finger, and so fasten the dial. It also enables him at pleasure to set the lock in the inoperative condition, leaving the dial free to be used in the ordinary manner.

What I claim as new, and desire to secure by Letters Patent, is—

1. The combination of a combination-lock dial and ring with a lock applied to the dial-ring so as to secure the dial fixedly in the ring to prevent its rotation, substantially as and for the purpose described.

2. The combination, with a combination-lock dial and its ring, of the stop P, with the gate H and spring I, substantially as and for the purpose described.

EMORY STOCKWELL.
